ARTICLE OF LUGGAGE

David Levitan, Brooklyn, N. Y.

Application March 23, 1954, Serial No. 29,651

Term of patent 14 years

(Cl. D87—5)

The figure shows a perspective view of the front, top and one end wall of an article of luggage embodying my new design.

Both end walls have the same appearance and contour and the rear wall is substantially plain.

I claim:

The ornamental design for an article of luggage, as shown and described.
